UNITED STATES PATENT OFFICE.

IRVING A. TAYLOR, OF WORCESTER, MASSACHUSETTS, ASSIGNOR TO RILEY STOKER CORPORATION, OF WORCESTER, MASSACHUSETTS, A CORPORATION OF MASSACHUSETTS.

FUEL-FEEDING MECHANISM FOR UNDERFEED STOKERS.

Application filed December 31, 1921. Serial No. 526,370.

This invention relates to a furnace stoker of the underfeed type and more particularly to means for controlling the feed of fuel thereto. Modern furnaces are commonly built up of a number of separate retorts, each furnace comprising a greater or less number of retorts according to the size of the boiler to be heated. It is often desirable to control and vary the fuel feed to a particular retort so that variations in the depth of the fuel bed may be eliminated and that an even fire may be maintained throughout the width of the furnace.

It is the object of my invention to provide improved means for thus varying the fuel feed by the use of lost motion connections between a driving crankshaft and each ram or plunger by which coal is fed to the separate retorts. This arrangement permits the use of a single continuously moving crankshaft extending the full width of the furnace and provided with a crank and crank pin for each retort, while at the same time separate control of the fuel feed at each retort is rendered possible.

My invention further relates to arrangements and combinations of parts which will be hereinafter described and more particularly pointed out in the appended claims.

A preferred form of my invention is shown in the drawings in which

Fig. 1 is a sectional elevation showing portions of a fuel feeding mechanism, together with my improved driving connections therefor;

Fig. 2 is a sectional plan view of certain of the parts shown in Fig. 1;

Fig. 3 is a perspective view, partly in section, of my improved driving connections,

Figs. 4 and 5 are transverse sectional elevations taken along the line 4-4 and 5-5 of Fig. 1, and

Fig. 6 is a diagrammatic view of a plurality of retorts and coal feeding mechanism therefor.

Referring to the drawings, I have shown portions of an underfed stoker which is, in general, of the usual type and comprises a hopper 10, a cylinder 11, a ram or plunger 12 slidable therein, a fuel chute or casing 13 leading from the cylinder to the retort, and a crank shaft 14 comprising a series of crank pins 15.

A recessed member or yoke 16 is pivotally

mounted within the ram 12 and is preferably supported upon the inner ends of short shafts or rods 17 extending through bearings 18 within the ram and secured in fixed position therein in any suitable and convenient manner as by bolts 19. The yoke 16 is thus firmly supported within the ram but is permitted to rock freely about the axis of the shafts 17 as a center. A cylindrical opening 20 extends longitudinally through the yoke 16 and this opening is provided with oppositely disposed grooves or guideways 21 (Fig. 4).

Aligned transverse openings 22 and 23 (Fig. 1) are formed in the yoke 16 and one or more openings 24 are formed in a connecting rod 25 which is slidable in the opening 20 of the yoke. When the parts are assembled, a cross pin 26 is inserted through the opening 22, this pin fitting the opening 24 in the rod 25 and the projecting ends of the pin being slidable in the grooves 21 of the yoke 16. The opening 23 is smaller than the pin 26 and is provided merely to permit a tool to be inserted for driving out the pin 26 when it is desired to remove the rod 25 from the yoke.

The connecting rod 25 is provided with a suitable connecting rod head 25^a by which it is attached to one of the crank pins 15 of the crank shaft 14. Stop lugs 27 are mounted in additional transverse openings in the yoke 16, these lugs being T-shaped in outline with their heads fitting within the grooves 21 when in operative position. In assembling the parts the T-shaped lugs are inserted in the transverse openings from within the yoke and are thereafter held from inward displacement by the rod 25.

As the rod 25 is drawn outward, the pin 26 slides freely along the grooves 21 until it engages the stop lugs 27, after which engagement it moves the ram 12 to withdraw the same from the cylinder 11.

A collar 28 is secured to the rod 25 by inserting a shearing pin 29 through the collar 100 and through one of several transverse holes 30 in the rod. As the rod moves toward the ram 12, the collar 28 presently engages the adjacent end of the yoke 16 and forms a positive driving connection to force the ram 12 into the cylinder 11.

The amount of lost motion between the rod 25 and the ram 12 may be reduced by

inserting one or more horse-shoe-shaped devices 31 between the collar 28 and the end of the yoke. The lost motion may also be adjusted by placing the shearing pin 29 in a different hole 30 in the rod 25. If greater shearing strength is desired, two or more collars 28 may be used, the collars 28 being in close contact and each being secured to the plunger 25 by its separate shearing pin.

10 My feeding mechanism thus operates to fully withdraw the feeding ram after each feeding stroke, but the effective advance feeding movement of the ram may be varied and adjusted to suit operating conditions by 15 changing the amount of lost motion between the rod and ram, either by moving the collar 28 or by inserting or removing one or more spacing devices 31.

10 While described with particular reference 20 to multiple retort stokers, my invention may be advantageously used in many cases with single retort stokers, particularly when several such stokers have a common air supply or are driven from a single or invariable 25 source of power.

Having thus described my invention, the advantages thereof will be readily apparent, and it will be further evident that changes and modifications can be made therein with- 30 in the spirit and scope thereof as set forth in the claims. Accordingly, I do not wish to be otherwise limited to the details herein disclosed but what I claim is:—

1. In an underfeed stoker, in combination, 35 a cylinder, a coal feeding ram slidable therein, a crank shaft, a connecting rod, a yoke transversely pivoted in said ram and having

an opening through which said rod is slid- 40 able, lugs in said opening held in position by said rod, a cross pin extending transversely of said rod in said opening and engaging said lugs to move said ram in one direction, and means moved by said connecting rod effective to move said ram in the opposite direction. 45

2. In an underfeed stoker, a cylinder, a coal feeding ram slidable therein, a crank shaft, a connecting rod having a cross pin, a yoke pivoted on a transverse axis in said ram and having an opening through which 50 said rod is slidable, said opening having grooves to receive the ends of said cross pin, a pair of stop lugs in said yoke having their inner ends disposed in said grooves and engaged by said cross pin to move said ram in one direction, and means moved by said connecting rod effective to move said ram in the opposite direction. 55

3. In an underfeed stoker, a cylinder, a coal feeding ram slidable therein, a crank shaft, a connecting rod, a yoke pivoted in 60 said ram and having an opening in which said rod is slidable, said rod having a pro- jection thereon and said yoke having an abut- 65 ment therein and engaged by said projection at a point within said yoke to limit sliding movement of said rod in said yoke in one direction, and means to adjustably limit sliding movement of said rod relative to said yoke in the opposite direction. 70

In testimony whereof I have hereunto af- fixed my signature.

IRVING A. TAYLOR.
